PETER MALACOS, OF WHEELING, WEST VIRGINIA.

PAPER-HANGING DEVICE.

1,288,093.

Specification of Letters Patent. Patented Dec. 17, 1918.

Application filed July 15, 1918. Serial No. 244,857.

To all whom it may concern:

Be it known that I, PETER MALACOS, a subject of the King of Greece, and resident of Wheeling, county of Ohio, and State of 5 West Virginia, have invented certain new and useful Improvements in Paper-Hanging Devices, of which the following is a specification.

This invention relates to paper-hanging 10 devices, and more particularly to a tool for applying wall paper to walls.

The primary object of the invention is to provide a simple, efficient and conveniently handled device whereby an adhesive may be 15 applied to wall paper and whereby such paper may be rapidly and conveniently applied to the walls of a room.

In describing the invention in detail, reference is herein had to the accompanying 20 drawings, in which—

Figure 1 is a perspective view of the invention, illustrating its application;

Fig. 2 is a similar view of the frame with the paste reservoir removed;

Fig. 3 is an elevation of one of the guide rollers, detached;

Fig. 4 is a similar view of the roller which carries the roll of paper;

Fig. 5 is a perspective view of the paste 30 reservoir, detached;

Fig. 6 is an enlarged cross-section of the reservoir;

Fig. 7 is an enlarged detail face view of the adjustable slide;

Fig. 8 is a section on line 8—8, Fig. 6; and

Fig. 9 is a cross section of the invention depicted in Fig. 1.

Referring to said drawings, in which like 40 designating characters distinguish like parts throughout the several views—

1 indicates the opposite parallel end members of a metal frame. Said members are of similar form and are connected at the 45 rear by a bowed frame member 2, said frame members being preferably composed of a single piece of flexible material bent into shape. Rotatably mounted in the lower part of each frame member 1 is a roller 3, preferably of wood, designed to receive thereon a roll 4 of wall paper to be applied to a wall. Said roller has a reduced end or neck 5 which is journaled in a hole or socket provided therefor in one of said end members, 55 and has its opposite end tapered, as shown

at 6, said tapered end being adapted to be received in a hole or socket provided therefor in the opposite end member. Said roller is movable lengthwise to protrude the tapered end 6 through the last mentioned hole 60 to effect removal and replacement of the same in the frame. A keeper plate 7 is pivoted in suitable position on the outer face of the end member by which the tapered end 6 of the roller is received, the same being 65 adapted to normally overlie the tapered end of said roller to prevent such lengthwise movement of the latter as would result in disengaging the same.

Disposed between the end members 1 in 70 overlying relation to a roll of paper carried by the roller 3 is a reservoir 8 for containing a liquid paste or adhesive to be applied to the reverse side of the paper. Said reservoir has its opposite ends 9, which are preferably composed of wood, disposed in abutting relation to the inner faces of the end members of the frame and attached to the latter by means of screws 10. The body 8^a of said reservoir is composed of sheet metal 75 within which said ends 9 are closely fitted. Said body is of curved or rounded form at its rearmost edge, which is located rearward of the paper roll, so that the paper strip 11 in unwinding from said roll rides closely 80 over said edge. Fitted snugly within the said body 8^a at said rear edge is a wooden feed member 12 having alined perforations 13 which register with perforations 14 in the rounded edge of said metallic body, said 85 perforations being designed to permit the adhesive paste to feed therethrough from the reservoir.

Said feed member has a longitudinal dovetail channel 15 therein which is open 95 throughout its length to the interior of the reservoir, and snugly fitted in and slidable longitudinally along said channel is a strip 16 of rubber or other suitable material having perforations 16^a therein spaced to correspond with the perforations 13 in the feed member 12 and which is designed to be moved longitudinally to place its said perforations in register with those of said feed member to permit the paste to feed, or to be 100 withdrawn to remove its perforations from registering relation to those of said feed member for preventing the passage of the paste. One end of said control strip 16 protrudes outward through an opening 17 pro- 110

vided therefor in an end 9 of the reservoir so that it may be grasped by the fingers for adjusting its position.

The reservoirs may be filled through any 5 conveniently located closable opening, as the opening 18 shown in Fig. 5.

Journaled in the opposite ends 1 of the frame at a point over the front or rounded edge of the reservoir is a roller 19 over which 10 the paper passes after having had the adhesive paste applied thereto in passing over said edge. A similar roller 20 is journaled in said ends 1 at a suitable point over the front edge of the reservoir, said roller being 15 designed to have the paper pass thereunder, or between it and said reservoir, as is clearly shown in Fig. 9. A pasting brush 21 has its ends mounted in a suitable manner in said frame-ends 1 in a position where- 20 in the bristles thereof will yieldingly exert pressure on the paper which extends upward in front of the roller 20.

The bowed member 2 of the frame carries a socketed member 22 designed to receive a 25 handle 23 whereby the device is supported by hand in the operation of the device.

In practice, the end of the paper roll 4 carried by the roller 3 is passed rearward to and upward over the perforated rear 30 edge of the reservoir to and over the roller 19, thence to and under the roller 20. In being drawn over said perforated edge, paste exuding through the perforations is spread over the rear face or back of the paper strip 35 and is still further distributed in passing over the roller 19. Having passed beneath the roller 20 the end of the strip may be applied to the wall which is to be papered, whereupon the device is moved downward 40 along the wall. In such movement the paper is yieldingly pressed against the wall and is smoothed out by the brush 21.

It will be noted that the device described is susceptible of various changes in the form 45 and arrangement of some of its parts. I do not therefore desire to be limited to the precise construction and arrangement herein shown and described, but reserve to myself such changes as fall within the scope of the 50 appended claims.

What is claimed is—

1. A paper-hanging device comprising a paste reservoir having a curved rear edge with perforations therein, means for controlling the passage of paste through said 55 perforations, guide rollers disposed over said reservoir, a roller adapted to carry thereon a roll of paper disposed beneath said reservoir, said guide rollers being 60 located over the front and rear portions, respectively, of said reservoir, and a brush located over the front edge of said reservoir, the paper strip as withdrawn from the paper roll being passed rearward to and upward over the perforated rear edge of said 65

reservoir, thence upward to and over the rear guide roller, thence to and beneath the front guide roller, and thence upward in front of the brush.

2. A paper-hanging device comprising a 70 roller adapted to carry thereon a roll of paper, a paste reservoir of oblong form in cross section located over said roller and having a curved edge located rearward with respect to said roller, said curved edge having 75 perforations therein, a member having perforations therein corresponding with those in said reservoir and adjustable into and out of register with the latter for opening and closing the same to the passage of 80 paste, the paper as it unwinds from said roller being adapted to pass rearward to and upward over said perforated edge and thence forward over the top of said reservoir, a brush located over the front edge 85 of said reservoir, and rollers located over the rear and front edges respectively of said reservoir for carrying the paper to and beneath said brush, the rear carrying roller being adapted to have the paper pass thereover and to distribute the paste, and the front carrying roller being adapted to have the paper pass thereunder and thence upward in front of said brush.

3. A paper-hanging device comprising a 95 frame, a roller mounted in said frame and adapted to carry thereon a roll of paper, a paste reservoir carried by said frame located over said roller and having a curved portion located rearward with respect to 100 said roller, said curved portion having closable feed-openings therein, rollers for carrying the paper as it unwinds from said roll to a point in front of said reservoir, one of said rollers being located over the curved 105 rear portion of said reservoir and having the paper pass thereover so that the latter is drawn rearward through and thence upward over and in contact with said curved portion, and a brush positioned to engage the 110 paper at a point in front of said reservoir.

4. A paper-hanging device comprising a frame, a roller mounted in said frame and adapted to carry thereon a roll of paper, a paste reservoir carried by said frame located 115 over said roller and having a curved portion located rearward with respect to said roller and adapted for having paper pass in contact therewith as it unwinds from said roll, closable feed-openings in said 120 curved portion of said reservoir, rollers carrying the paper as it unwinds to a point in front of said reservoir, one of said rollers being disposed to engage the reverse side of the paper and adapted to serve as a paste distributor, and a brush disposed over said reservoir and projecting in front of the latter in position to exert smoothing and applying pressure to paper after the latter has 125 passed from the last of said rollers.

5. A paper-hanging device comprising a frame, a roller mounted in said frame and adapted to carry thereon a roll of paper, a paste-reservoir carried by said frame located 5 over said roller and having a portion located rearward with respect to said roller and adapted for having paper pass in contact therewith as it unwinds from said roll, said rearward portion of the reservoir having a 10 channel in the interior face thereof and having feed openings leading outward from said channel, a member disposed within said channel and having openings therein corresponding to said feed openings, said mem- 15 ber being adjustable to carry its openings into and out of register with said feed openings, and a brush mounted over the front portion of said reservoir, and adapted to apply sealing pressure to a strip of paper as the latter is passed in front thereof in 20 unwinding from said wall.

In testimony whereof, I affix my signature in presence of two subscribing witnesses,

PETER MALACOS.
